UNITED STATES PATENT OFFICE.

HENRY A. COWLES, OF WESTFIELD, MASSACHUSETTS, ASSIGNOR TO THE
BAY STATE WHIP COMPANY, OF SAME PLACE.

WHIP.

SPECIFICATION forming part of Letters Patent No. 397,456, dated February 5, 1889.

Application filed June 8, 1888. Serial No. 276,482. (No model.)

To all whom it may concern:

Be it known that I, HENRY A. COWLES, a citizen of the United States of America, residing at Westfield, in the county of Hampden and State of Massachusetts, have invented new and useful Improvements in Whips, of which the following is a specification.

This invention in whips relates particularly to the formation of the cores thereof, the object of which is to so improve the construction of a whip that it will be capable of all required elasticity and yet be possessed internally of a considerable tensile resistance, whereby the whip will be normally retained undeflected, will have the nature of a whale-bone whip, and will be most durable, all at a minimum cost of production; and the invention consists in the employment and combination of the various parts, all substantially as will hereinafter more fully appear, and be set forth in the claim.

Reference is to be had to the accompanying drawings, in which Figure 1 is a portion of the whip, partly in side elevation, partly in central longitudinal section, and at one end with the outer covering portions shown as successively stripped from the relatively next internal parts for better illustration. Fig. 2 is a cross-section of the whip shown in Fig. 1. This whip contains the following elements: The core center, *a*, is of wire or wires, preferably of steel wires spring-tempered, as well known in the art. Surrounding the center *a* there is a number of strands, *b*, of "cat-gut," stout linen thread, or analogous mate-

rial, extending lengthwise of the core, and, of course, parallel to each other. A plaited covering, *c*, of textile material, covers the longitudinal strips *b* and completes the core of the whip. Steel cores to whips are not new, and such cores have been covered by a braided or plaited covering, but, so far as is known, without the interposed longitudinal strips *b*. After the construction of the core the whip is made up by applying the sidings *d* of rattan, which are cemented to said core-plaiting and are rounded in the usual manner and have a surface-finish of stain and varnish, or have the usual outer plaited covering, *e*, applied thereto in any of the usual ways well known to whip-manufacturers.

The employment of the longitudinally-extending strands laid upon the metal center and held thereon by the textile plaiting is important, as such strands serve to strengthen the whip and afford in a considerable degree a tensional resistance against the bending of the whip, and tend to keep the same straight.

What I claim as my invention is—

A whip having a central steel core-piece surrounded by parallel longitudinal strands of catgut or fibrous material, a plaited core-covering, and a surrounding whip-cover of usual material connected to said whip-core, substantially as described.

HENRY A. COWLES.
